UNITED STATES PATENT OFFICE.

JOHN KIEWICZ, OF BOSTON, MASSACHUSETTS, ASSIGNOR TO THE REECE BUTTON HOLE MACHINE COMPANY, OF BOSTON, MASSACHUSETTS, A CORPORATION OF MAINE.

THREAD-TRIMMER FOR SEWING-MACHINES.

1,338,374.

Specification of Letters Patent.

Patented Apr. 27, 1920.

Application filed April 10, 1918, Serial No. 227,622. Renewed December 15, 1919. Serial No. 345,124.

To all whom it may concern:

Be it known that I, JOHN KIEWICZ, a citizen of the United States, residing at Boston, county of Suffolk, State of Massachusetts, have invented an Improvement in Thread-Trimmers for Sewing-Machines, of which the following description, in connection with the accompanying drawing, is a specification, like characters on the drawing representing like parts.

This invention relates to sewing machines and particularly to buttonhole sewing machines, and the object of the invention is to provide a novel device for severing the under thread and stay-cord close to the work at the end of the stitching operation on each buttonhole. The device herein shown is in some respects similar to that illustrated in my co-pending application Se. No. 203,889, filed November 26, 1917, and is in the nature of an improvement on said device.

The device illustrated in said application comprises two jaw members carried by the clamp plate which is removable from the frame, means to move the jaw members into position to grip the under-thread and stay-cord beneath the work at the end of the stitching operation and then to retract said closed jaw members so as to draw out a length of both the stay-cord and the under-thread, and a knife which is operative after the jaw members have thus been retracted to cut the under-thread and stay-cord close to the work.

In my present invention I retain the two jaw members, but construct them so that they operate not only to draw out the under-thread and stay-cord, but also to cut the latter, and I have also simplified the mechanism for operating the jaws.

In order to give an understanding of my invention, I have illustrated in the drawings a selected embodiment thereof which will now be described, after which the novel features will be pointed out in the appended claims.

In the drawings, Figure 1 is a side view of a portion of the sewing machine having my improvements applied thereto;

Figs. 2, 3, 4 and 5 are plan views of the clamp plate with the thread-cutting mechanism thereon, said views showing the mechanism in different relative positions;

Fig. 6 is an underside view of the front

end of the bed-plate showing the ends of the 55 actuating levers;

Fig. 7 is an enlarged section on the line 7—7, Fig. 2;

Fig. 8 is an enlarged section on the line 8—8, Fig. 5;

Fig. 9 is a detail sectional view showing the manner in which the block 11 of the work-holding means retains the jaw members in their retracted position.

1 indicates the bed-plate of the sewing 65 machine from which rises the head or overhanging arm 2 in which reciprocates the usual needle-bar 4 which carries the upper needle 3. Situated beneath the bed-plate 1 is an under-thread-handling mechanism of 70 any usual type which is indicated generally by 5 and which is provided with the throat-plate 12 having the aperture 13 through which the under-thread 6 and stay-cord 7 are delivered.

The work in which the buttonhole is being formed is indicated at *w* and is held during the sewing operation by work-holding means of any usual type which is given its feeding movement during the stitching 80 on a buttonhole by the usual feed cam 42. The work-holding means is herein illustrated as comprising a clamp-plate 8 on which the work rests and work-clamps 9 that clamp the work to the plate, said work 85 clamps being carried by arms 10 supported by a block 11 that is pivotally connected to the clamp-plate 8 so as to allow the work clamps to close onto the work or to be opened to release the work, all as usual in 90 buttonhole-sewing machines.

Since the present invention relates solely to the device for cutting and trimming the under-thread and stay-cord close to the work at the end of the stitching operation on each 95 buttonhole, I have not thought it necessary either to illustrate or describe further the buttonhole sewing machine.

My improved under-thread and stay-cord-trimming mechanism comprises two jaw 100 members 14 and 15 which are situated directly above the clamp-plate 8 and between the latter and the work *w* and which are pivotally connected together by the pivotal stud 16, said stud extending through and 105 beneath the jaw members and the lower end thereof operating in a guiding slot 17 formed in the clamp-plate 8. The jaw mem-

bers thus are capable of having a bodily movement toward and from the throat-plate 12 and also an opening and closing movement about the pivot 16.

- 5 The jaws 14 and 15 are each provided with a thread-receiving notch 26 and with a beak 27, the beaks being so arranged that when the jaws are closed they will overlap each other.
- 10 During the sewing operation on the buttonhole the jaws 14 and 15 are in their retracted open position shown in Fig. 2, in which position they are situated between the throat-plate 12 of the under-thread mechanism and the front of the machine. At the end of the stitching on a buttonhole the two jaws 14 and 15 are moved bodily toward the throat-plate while in their open relation so as to carry them into the position shown 15 in Fig. 3. During this movement the beaks 27 pass either side of the under-thread 6 and stay cord 7 that extend from the work through the throat-plate, so that said under thread and stay-cord are situated opposite 20 the notches 26. The jaws are then closed sufficiently to cause the beaks 27 to overlap slightly so that the notches 26 form a closed aperture in which the under-thread and stay-cord are received. After the jaws have 25 been thus closed they are moved backwardly bodily into the position shown in Fig. 4 thereby drawing out from the source of supply a length of under-thread and stay-cord, after which the under-thread and stay-cord 30 are cut close to the work. This is accomplished by providing the notches 26 with cutting edges 28 and by providing means for giving the jaws a further closing movement, as shown in Fig. 5, so that the cutting 35 edges 28 will act on the stay-cord and under-thread with a shearing cut thereby to sever them.

I will now describe the mechanism I prefer to employ for giving the jaws 14 and 15 the above-described sequence of movements.

The means I employ for holding the jaws in their retracted position during the stitching of the buttonhole is controlled by the work clamp, so that when the work-clamps 50 9 are raised to unclamp the work the jaws will be moved forwardly from the position shown in Fig. 2 to that shown in Fig. 3. The upper end of the stud 16 is received in a slot 30 formed in the end of a lever 31 55 which is pivoted to the clamp plate 8 at 32. Said lever has a strut 33 connected thereto, the end of which engages the block 11 of the work clamp when said work clamp is in operative clamping position. The lever 31 60 has an arm 34 extending therefrom to which is connected a pulling spring 35 that tends to swing the lever 31 to the right. So long as the work clamp 9 is lowered, the strut 33 will engage the block 11 and hold the jaws 65 14 and 15 in their retracted position against

the action of the spring 35. When the work-clamps 9 are raised to unclamp the work, then the lower edge of the block 11 is carried above the end of the strut member 33 thereby releasing the latter and allowing 70 the spring 35 to move the jaws forwardly into the position shown in Fig. 3.

The closing movement of the jaws is controlled by a lever 21 pivoted to the frame at 75 22. This lever is provided with a pin 20 which operates in a slot 19 formed in the rear end 18 of the jaw 15 and also operates in an opening 24 formed in the rear end 23 of the jaw 14. The opening 24 is provided with the inclined edge 25. The lever 21 is 80 acted upon by a spring 36 which tends to swing it inwardly toward the right and thereby maintain the pin 20 at the inner end of the slot 19 and opening 24. When the pin 20 is in this position the jaws are in open 85 relation, as shown in Figs. 2 and 3. After the jaws have been moved forwardly into the position shown in Fig. 3 the lever 21 is swung backwardly, during which movement the pin 20 acts against the inclined wall 25 90 of the opening 24 and against the wall of the slot 19 thereby swinging the jaws into the partially-closed position shown in Fig. 4. This is done while the jaws remain in their forward position shown in Fig. 3 so 95 that the beaks 27 will pass behind the under-thread and stay-cord, thus locking them in the opening formed by the notches 26.

The length of the slot 19 is such that when the swinging movement of the lever 100 21 has brought the pin 20 to the rear end of the slot, the jaws will be in their partially-closed position shown in Fig. 4. The lever 21 has a range of movement greater than necessary to bring the pin 20 to the rear end 105 of the slot 19, so that during the further swinging movement of said lever, the pin 20 will act against the end of the slot 19 and will thereby move the jaws bodily to the left into the position shown in Fig. 4, this 110 movement being accomplished while the jaws are retained in their partially-closed position. This bodily backward movement of the jaws results in pulling out a length of under-thread and stay-cord, as shown in 115 Fig. 4, and during such movement the stud 16 travels backwardly in the slot 17.

The means for giving the lever 21 its backward swinging movement is similar to the corresponding means shown in my above-mentioned co-pending application, and it comprises an elbow-lever 37 pivoted to the underside of the bed plate at 52 and which is acted upon by a spring 53 that normally holds it in the position shown in Fig. 5. One 125 arm 54 of this elbow-lever is engaged and actuated by a lever 39 pivoted to turn about a stud 40, and the other arm 55 of said elbow-lever is adapted to contact with a pin or projection 38 depending from the lever 130

21. The swinging movement of the lever 39 will, therefore, operate through the elbow-lever 37 to give the lever 21 the necessary rearward swinging movement. The lever 39 is actuated by a cam 41 which is rigid with the usual main cam 42 of the buttonhole sewing machine by which the work-holding means is given its feeding movement. This cam 41 is similar to the corresponding cam 5 illustrated in my co-pending application and is constructed so that at the proper time in the cycle of operations it will actuate the lever 39 thereby to cause the rearward movement of the lever 21.

15 For cutting the stay-cord after the jaws have been pulled backwardly into the position shown in Fig. 4, I employ a lever 43 also pivoted at 40 and acted upon by the cam 41, the end 44 of said lever being adapted to 20 engage a depending finger 45 extending from the end 23 of the jaw 14. The shape of the cam 41 is such that after the lever 39 has been actuated thereby to cause the jaws 14 and 15 to be retracted into the position 25 shown in Fig. 4, the lever 43 will be actuated to bring the end 44 thereof against the finger 45 thereby giving a swinging movement to the jaw 14 into the position shown in Fig. 5 which will cause the shearing 30 edges 28 to coöperate to cut the under-thread and stay-cord. The aperture 24 is made large enough so as to permit this cutting movement of the jaw 14.

The jaw 14 is shown as having a wedge-shaped projection 46 which is adapted to enter under a hold-down member 47 carried by the jaw 15, the purpose of this being to insure that the cutting edges 28 will be held in shearing relation during the cutting operation.

The jaws 14 and 15 are normally held open by means of a spring 48 and an additional spring 49 is provided which only becomes compressed after the jaws are closed. 45 The spring 49 is relatively stiff and the purpose of it is to give the jaws an initial opening movement after the lever 43 has been operated to effect the severing of the under-thread and stay-cord.

50 In actual practice the jaws will be covered by a cover-plate 50, said plate being so shaped that it will cover the jaws when they are in their retracted position, but when the jaws are moved into the position shown in 55 Fig. 3 they will project slightly beyond the edge 51 of the plate. The location of the edge 51 is indicated by the dotted line 51 in Figs. 2, 3 and 4. The work *w* rests on the plate 50 and said plate, therefore, protects the work from the thread-trimming mechanism.

While I have herein illustrated a selected embodiment of the invention, I do not wish to be limited to the constructional features 60 shown.

I claim:

1. In a sewing machine, the combination with work-holding means, of stitch-forming mechanism including under-thread-handling mechanism, a pair of pivotally-connected jaw members, each having a thread-receiving notch and a beak, means operative at the end of a stitching operation to move the jaw members into position to engage the thread, means to partially close 70 said jaws thereby to bring the beaks into overlapping relation and to inclose the thread in the notches and then to move the jaws bodily to draw out a length of thread, and means to give the jaws a final closing 75 movement thereby to sever the thread.

2. In a sewing machine, the combination with work-holding means, of stitch-forming mechanism including under-thread-handling mechanism, a pair of pivotally-connected jaw members situated beneath the work and each provided with a thread-receiving notch and a beak, means operative at the end of a stitching operation to move 80 said jaws into position to engage the under-thread beneath the work, means to partially close said jaws thereby to bring the beaks into overlapping relation and to inclose the under-thread in the notches of the jaws and then to move the jaws bodily to draw out a 85 length of under-thread, and means to give said jaws a final closing movement thereby to sever the thread.

3. In a sewing machine, the combination with work-holding means, of stitch-forming mechanism including under-thread-handling mechanism, a pair of pivotally-connected jaw members carried by the work-holding means beneath the work, each jaw member having a thread-receiving notch 100 provided with a cutting edge and a beak, means operative at the end of a stitching operation to move the jaws into position to engage the under-thread, means to partially close said jaws thereby to bring the beaks 105 into overlapping relation and then to move the jaws bodily and draw out a length of under thread, and means to give said jaws a final closing movement thereby to sever 110 said thread.

4. In a sewing machine, the combination with a frame, of work-holding means removable therefrom and comprising a clamp plate, stitch-forming mechanism including an under-thread-handling mechanism provided with a throat-plate, a pair of pivotally-connected jaw members carried by the clamp plate, and each provided with a notch having a cutting edge and a beak beyond the notch, means operative at the end 120 of a stitching operation to move said jaws on the clamp plate into thread-engaging position, means to partially close said jaws thereby to bring the beaks into overlapping 125 relation and then to move the jaws bodily on 130

the clamp plate to draw out a length of thread from the throat-plate, and means to give said jaws a final closing movement thereby to sever the thread.

5. In a sewing machine, the combination with work-holding means, of stitch-forming mechanism including under-thread-handling mechanism, a pair of pivotally-connected jaw members carried by the work-holding means and each provided with a notch having a cutting edge and a beak beyond the notch, means operative at the end of the stitching operation to carry the jaw members into thread-engaging position, a lever acting on the jaw members and operating first to partially close said jaws thereby to inclose the thread in the thread-receiving notches and then to move the jaws bodily to draw out a length of under-thread, and means acting on one jaw to complete the closing movement of the jaws thereby to sever said thread.

6. In a sewing machine, the combination with work-holding means, of stitch-forming

mechanism, a pair of pivotally-connected 25 jaw members, each having a thread-receiving notch provided with a cutting edge and a beak beyond the notch, one jaw member having at its rear end an inclined slot, and the other an opening provided with an oppositely-inclined edge, a pivoted lever having a pin extending through said slot and opening, means to swing the lever to carry the pin to the rear end of the slot and cause it to act against the inclined side of said 30 opening whereby the jaws are closed sufficiently to cause the beaks to overlap so that the thread is inclosed in the notches, said means operating to give the lever a further swinging movement thereby to retract the jaws bodily, and means acting on the jaw having the opening to give it a further closing movement thereby to sever the thread.

In testimony whereof, I have signed my 45 name to this specification.

JOHN KIEWICZ.
